UNITED STATES PATENT OFFICE.

DANA PARKS, OF BOSTON, MASSACHUSETTS.

SELF-LEVELING SHIP'S BERTH.

SPECIFICATION forming part of Letters Patent No. 224,469, dated February 10, 1880.

Application filed October 8, 1879.

To all whom it may concern:

Be it known that I, DANA PARKS, of Boston, Suffolk county, Massachusetts, have invented an Improvement in Self-Leveling Ships' Berths, of which the following is a specification.

My invention relates to the sleeping-berths used upon ocean-steamer and passenger-vessels; and it consists in a certain novel arrangement and construction whereby the berth will at all times remain poised in a horizontal plane, no matter what the movement of the vessel may be.

My said invention will first be fully described, and then more briefly defined and specified in the claims.

In the drawings forming part of this specification, Figure 1 is a perspective view illustrating my invention. Fig. 2 is a vertical longitudinal section of Fig. 1. Fig. 3 is a detail view, showing the foot of the berth with the supports by which the berth is sustained, and by which it is allowed to move freely in both directions.

The same letters of reference indicate like parts in all the figures.

A in the drawings represents a portion of an ordinary state-room upon a sea-going vessel, and B indicates the berth, of which there are always two in each state-room, one placed above the other. At the head and foot of the berth B are placed metallic supporting-blocks C, (vide Fig. 3,) having at the lower end a trunnion, D, which engages with a shell, E, attached to the center of the end of the berth, and as near the top as possible, in order to locate the center of gravity as far as possible below the point of support.

In order to render the connection between the trunnion D and shell E perfectly secure it may, perhaps, be found desirable to form a spline upon one, running in a groove formed in the other; but I do not apprehend that this will be a necessity, since, with accurate workmanship, the end-thrust of the berth will be received upon the supporting-blocks C, which are perfectly supported behind upon the friction-ways F, hereinafter to be described, so that no space is allowed for the shell to slip off the trunnion.

The supporting-block C is suspended by means of a chain or other suitable device, G, attached to the block in any suitable manner. From the point of attachment the chain rises to a pulley, I, to the periphery of which it is attached, as shown in Fig. 2. This pulley I propose to journal upon friction-sheaves, in order to impart perfect ease of motion, since it is through these elements that I provide for the end motion of the berth.

It will be noticed that the chain winds upon the head-pulley in one direction and upon the foot-pulley in an opposite direction. In order to prevent the chain unwinding by the weight of the parts, and thus dropping the berth to the full length of the chains, I connect said pulleys by a rod or bar, K, attached at its ends to a projecting piece formed upon the circumference of the pulley, as shown at a. The bar K is weighted with a light mass of metal, K', to give stability of motion to the pulleys.

Behind the metal blocks C are placed ways F, which are set into the bulk-heads and provided with a series of friction-rolls, b b, which afford an easy friction-bearing to the supporting-block C, whereby the end motion of the berth is rendered smooth and all unnecessary friction eliminated.

The operation of my berth is as follows: When the weight of the occupant is placed therein it is evident that all lateral motion or rocking of the ship will be compensated by the pivotal supports or trunnion and shell D E, so that the berth will at all times remain in a horizontal position so far as lateral motion is concerned. The pitching or fore-and-aft motion of the vessel is taken up or compensated by the pulleys I and chains G, the *vis inertiae* of the weighted connecting-rod loaded with the weight K' being sufficient to secure the necessary end motion. It should be noted that in the case of vessels of ordinary size this motion is comparatively small.

One great advantage of my invention is that I am able to construct the ordinary passenger-berth in accordance therewith without any sacrifice of space, while the simplicity of the mechanism, the whole support being located at the head and foot only, enables me to se-

cure the necessary action with a small number of mechanical elements and economy of expenditure.

5 The friction-ways F may be set into the bulk-heads of the state-room a suitable distance to secure a perfect economy of space, it being only necessary to leave space enough between the ends of the berth and the bulk-heads to admit the small end movement of the berth.

10 The rod K is a convenience to the occupant of the state-room in entering the berth, as it affords a grasp for one or both hands. In practice the upper berth is so placed that its casing or frame partly covers and almost 15 wholly conceals the two pulleys from which the lower berth is suspended.

Having thus fully described my invention, what I claim, and desire to secure by Letters Patent of the United States, is—

20 1. A ship's berth supported entirely at head and foot by movable trunnion-blocks, which are suspended from connected sheaves provided with a controlling-weight, whereby both the lateral and the fore-and-aft motion is compensated, substantially as set forth.

25 2. A swinging ship's berth supported entirely at head and foot by movable trunnion-blocks, in combination with pulleys to which

said blocks are connected and a weighted rod connecting said pulleys, substantially as and for the purpose set forth.

3. The combination of a swinging berth with movable trunnion-blocks at head and foot, a chain or other flexible suspending device attached to said trunnion-blocks, a pulley over 35 which said chain is wound, and a bar connecting the pulley at the head with that at the foot, said bar being suitably weighted, as and for the purpose set forth.

4. The combination, with the swinging berth 40 B, of the trunnion-blocks C and friction-ways F, having friction-rolls b b b, as and for the purpose set forth.

5. The combination, with the swinging berth B, of the movable trunnion-blocks C, the ways 45 F, having friction-rolls b b, the suspending-chains G, the pulleys I I, and the weighted connecting-bar K, all substantially as and for the purpose set forth.

In testimony whereof I have signed my 50 name to this specification in the presence of two subscribing witnesses.

DANA PARKS.
